BARREL

Bertil T. Lindell, Detroit, Mich., assignor to The Murray Corporation of America, a corporation of Delaware

Application May 29, 1933, Serial No. 673,363

4 Claims. (Cl. 220—10)

My invention relates to barrels and particularly to an all-metal barrel of double wall construction wherein the outer reinforcing portion supports the inner liquid container portion.

5 In the co-pending applications of Charles H. Widman, Serial No. 670,663 filed May 12, 1933, and assigned to the assignee of the present invention, a liquid tight all-metal barrel was illustrated, described and claimed wherein the inner container portion formed a unit which was strengthened and reinforced by cap elements which were supported thereon.

In practicing my invention, I employ the inner liquid container portion as described and claimed 15 in the above mentioned co-pending applications and entirely encompasses the portion in an outer reinforcing shell which is of heavy gauge material and which is self-contained, forming a complete unit which is secured to the inner liquid 20 container portion in such manner as to be a support therefor. In this type of construction the outer reinforcing shell is the support for the inner liquid container portion. The inner liquid container portion may be made of light gauge 25 material since the heavy reinforcing portion provides protection for the inner liquid container portion.

Accordingly, the main objects of my invention are: to provide a liquid tight barrel wherein 30 an inner liquid container portion is supported and reinforced by a heavier outer encompassing portion; to provide end reinforcing members for the liquid container portion which contacts the liquid container portion at the bilge to form a support therefor; to span the two reinforcing cap 35 portions by a strong metal band which unites the cap portions to form a unit which protects the inner liquid container portion; to provide a bung for the barrel which has shouldered portions 40 for receiving the metal of the containing and reinforcing portions of the barrel which is thereafter flanged over and brazed, soldered, welded or otherwise secured to the metal in a liquid-tight manner; to provide a bung at the bilge of the barrel which is flush with the bilge and which is provided with serrations forming 45 grooves into which the wood of the bung may swell upon being soaked with the contained liquid to tightly engage the grooves and lock the bung against the pressure of the liquid developed within the liquid container portion; to reinforce the chime or handhold portions of the barrel by annular preformed portions or arcuate preformed portions as the case may be; and, in general, to provide an all-metal barrel having inner

and outer metal unit portions which is simple in construction and economical of manufacture.

Other objects and features of novelty of my invention will be either specifically pointed out or will become apparent when referring, for a better understanding of my invention, to the following description taken in conjunction with the accompanying drawing, wherein:

Figure 1 is a view, in elevation, of a barrel of the tight type embodying features of my invention,

Fig. 2 is an enlarged sectional view of the structure illustrated in Fig. 1, taken on the line 2—2 thereof,

Fig. 3 is an enlarged sectional view of the 15 structure illustrated in Fig. 1, taken on the line 3—3 thereof,

Fig. 4 is a plan view of the barrel illustrated in Fig. 1, and

Fig. 5 is an exploded plan view of structure 20 similar to that illustrated in Fig. 3, showing a modified form thereof.

Like the barrels in the above mentioned co-pending applications, the inner container of the present barrel is made up of like pressed metal 25 elements 11. The elements are preferably provided with an outwardly directed flange 12 which abut together to form a joint, which is readily welded, preferably through the melting of the flanges 12. The inner container thus formed is 30 made of comparatively light gauge material in view of the fact that it is entirely protected by the outer reinforcing portion 13 of the barrel. This portion is made up of two like pressed metal elements 14 which are press fitted over the 35 inner liquid container portion 11, being joined thereto, at the bilge, by the flanges 15. The flanges form a support for the inner liquid container portion. The reinforcing portions 14 are similar in construction to that of the above men- 40 tioned co-pending application having step portions 16 which add strength to the barrel and a web portion 17 in combination with an annular flange portion 18 which forms a surface upon which the barrel may be rolled on tracks or 45 across a flat floor. Chimes 19 are provided on both ends of the barrel to form handholds and stacking ends which are herein shown as being reinforced by annular, arcuately shaped elements 21.

After the reinforcing end caps 14 have been spot welded to the inner liquid container portions 11 and the portions are welded together, a bilge band 22 is applied over the annular flange portion 18, having side edges which are like arc- 50 55

uately shaped to encompass the flanges 18 and are abutted together at the bilge bung 24 of the barrel. The band is welded to each section, at 25, to form a unit construction with the two reinforcing elements 14. The outer reinforcing portions 14 and the belt 22 are made of heavier material than the inner liquid containing portion 11 and thereby support and protect the inner portion from damage.

10 The bung 24 comprises an annular portion 26 having a top flange 27, the former of which extends through the belt 22 to engage an inner flange 28 on the inner liquid containing portions 11 to be brazed, welded, or otherwise secured thereto in a liquid-tight manner. The outer flange 27 of the bung 24 is welded directly to the belt 22 at the time the belt is welded together. The bung is provided with a plurality of grooves 29 which form lands on the inner 15 cylindrical or frusto conical surface of the bung, for the purpose of having the wood plug expand when saturated with the liquid contained in the barrel, to be forced within the grooves to thereby form the tight engagement to prevent the pressure, which may be developed by the liquid 20 within the barrel, from forcing the plug from the bung.

At the top of the barrel, the inner liquid container portion 11 and the reinforcing portion 14 are joined by a bung 31 which is provided with shoulder portions 32 for receiving the ends of the metal about apertures in the portions. The edges of the bung are then penned or flanged over at 33 to form an anchor between the bung 35 and the metal and a brazing solder may be employed additionally for sealing the bung to the metal. It is to be understood that the bung is secured to the inner container portion 11 first and thereafter secured to the outer reinforcing 40 portion 14 of the barrel. While the inner cylindrical surface of the bung may be left smooth, or corrugated as above described, I have illustrated a thread provided thereon to which a standard fitting may be secured.

45 It is to be understood that insulating material 30 as described in the latter of the above mentioned co-pending applications, may be provided between the inner and outer shell portions of the barrel and between the inner portion of 50 the barrel and the belt 22 for the purpose of substantially insulating the barrel. When such insulation material is not employed, the air trapped between the inner and outer portion of the barrel will provide insulation to a satisfactory degree.

55 Referring to Fig. 5, I have illustrated a modified form of construction wherein the chime reinforcing element 21 is made up of three arcuate sections 35, each being 120 degrees in length 60 and having the cross section as illustrated in Fig. 2. The three sections are then welded to the barrel and to each other to form a complete reinforcing annular support. The advantage of constructing the reinforcing element 21 in sections is to eliminate the waste of metal which 65 would occur if the reinforcing element were stamped in a single piece. By stamping them in

sections, as illustrated in Fig. 5, substantially no waste of material results.

While I have described and illustrated several embodiments of my invention, it will be apparent to those skilled in the art that various changes, omissions, additions, and substitutions may be made therein without departing from the spirit and scope of my invention, as set forth in the accompanying claims.

I claim as my invention:

10 1. An all-metal barrel including, in combination, an inner liquid containing portion made up of like elements which are secured together near the bilge portion of the barrel, outer pot shaped reinforcing elements of heavier material secured to the liquid containing portion near the bilge and in spaced relation to each other, said elements having rolling beads thereon and a belt provided at the bilge portion spanning the reinforcing elements and rigidly secured there- 15 to in overlapping relation to said beads to maintain the two reinforcing elements in unit engagement and to reinforce said beads.

2. A barrel of the all-metal type having an inner liquid containing portion, outer pot shaped 25 reinforcing portions of heavier material which encompass the inner liquid container portion and engage the bilge portion thereof said elements having rolling beads thereon, and a belt bridging the reinforcing portions and rigidly se- 30 cured to the outer reinforcing portions in overlapped relation to said beads.

3. An all-metal barrel fabricated from sheet metal stampings which comprises, an inner liquid 35 containing portion and outer pot-shaped reinforcing portions in spaced relation to said liquid containing portion, except for the portions which support the inner liquid containing portion, said reinforcing elements being spaced 40 from each other and having rolling beads formed thereon, a band united to said spaced reinforcing portions in overlapping relation to said rolling beads and extending circumferentially around the barrel forming with said reinforcing portions an outer unit construction, and insulating material provided in the space between the inner and outer portions of the barrel.

4. An all-metal barrel fabricated from sheet metal stampings which comprises, an inner liquid 50 containing portion, outer pot-shaped reinforcing portions, mounted in spaced relation with respect to said inner portion, said outer portions engaging the inner portion of said barrel throughout annular areas on either side of the axial central portion thereof and having 55 rolling portions adjacent said areas, a band extending circumferentially around the barrel, spaced from said inner portion and having its edge portion united to said pot-shaped reinforcing elements in overlapped relation to said 60 rolling portions to form therewith a unitary outer construction, and insulating material provided in the space between the inner and outer portions of said barrel.

BERTIL T. LINDELL.
